(57) **CLAIM**

The ornamental design for a microphone stand with boom arm, as shown and described.

DESCRIPTION

FIG. 1 is a front, right perspective view of an extended shape of a microphone stand with boom arm when the extension is maximized;

FIG. 2 is a front, left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right perspective view of an extended shape of the microphone stand with boom arm when the extension is minimized;

FIG. 10 is a rear, right perspective view thereof;

FIG. 11 is a front elevation view thereof;

FIG. 12 is a rear elevation view thereof;

FIG. 13 is a right side elevation view thereof;

FIG. 14 is a top plan view thereof;

FIG. 15 is a bottom plan view thereof;

FIG. 16 is a front, right perspective view of a folded shape of the microphone stand with boom arm;

FIG. 17 is a rear, right perspective view thereof;

FIG. 18 is a front elevation view thereof;

FIG. 19 is a rear elevation view thereof;

FIG. 20 is a left side elevation view thereof;

FIG. 21 is a right side elevation view thereof;

FIG. 22 is a top plan view thereof; and

FIG. 23 is a bottom plan view thereof.

FIG. 24 is a partial enlarged view of an area labeled 24 in FIG. 1.

FIG. 25 is a partial enlarged view of an area labeled 25 in FIG. 1.

FIG. 26 is a partial enlarged view of an area labeled 26 in FIG. 1.

FIG. 27 is a partial enlarged view of an area labeled 27 in FIG. 9.

FIG. 28 is a partial enlarged view of an area labeled 28 in FIG. 9.

(Continued)

FIG. 29 is a partial enlarged view of an area labeled 29 in FIG. 9.

FIG. 30 is a partial enlarged view of an area labeled 30 in FIG. 16; and,

FIG. 31 is a partial enlarged view of an area labeled 31 in FIG. 16.

The dot dash broken lines surrounding portions of the microphone stand with boom arm in FIGS. 1, 9, and 16 and illustrated in the enlarged views of FIGS. 24 through 31, form no part of the claimed design.

1 Claim, 30 Drawing Sheets
